UNITED STATES PATENT OFFICE.

EDWARD M. JONES, OF MACON, GEORGIA.

DOOR FOR CREMATORIES.

1,102,668.

Specification of Letters Patent.

Patented July 7, 1914.

Application filed December 18, 1913. Serial No. 807,516.

To all whom it may concern:

Be it known that I, EDWARD M. JONES, a citizen of the United States, residing at Macon, in the county of Bibb and State of Georgia, have invented a new and useful Door for Crematories, of which the following is a specification.

This invention relates to doors for crematories, it being particularly designed for use in connection with a crematory of that type disclosed in a copending application filed by me.

One of the objects of the invention is to provide a crematory door which will tightly seal the opening in the crematory so as thus to prevent interference with the drafts within the crematory.

A further object is to provide a door having means whereby currents of cool air are permitted to circulate therein, thus preventing injury to the door such as might result from the intense heat to which it is subjected.

A further object is to provide a door of improved construction, the inner surface of which is made up of fire brick held to the frame of the door in a peculiar manner.

A further object is to provide a door which is easy to move and which is simple and durable in construction.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a front elevation of the door, portions of the adjacent structure being shown. Fig. 2 is a section on line A—B Fig. 1. Fig. 3 is a plan view. Fig. 4 is a section on line C—D Fig. 2. Fig. 5 is a detail view of one of the wedge engaging brackets.

Referring to the figures by characters of reference E designates a portion of a crematory in which is formed a door opening F. The wall of the crematory is provided along the top of the opening F with a face plate

1 which extends throughout the width of the opening F and is provided, at its center and adjacent each end, with a bracket 2 formed with a depending lip 3, the tips of all of the brackets converging in one direction toward the face plate 1. The brackets are of different widths, as will be seen by referring to Fig. 3, the bracket at one end being wider than the middle bracket and the bracket at the other end being narrower than the middle bracket.

A rail 4 extends across the door opening F at the bottom thereof and outside of the crematory and serves to support and guide wheels 5 on which the door proper is mounted. As shown in the drawings the door consists of a frame 6 with side bars having outturned inner flanges 7 and inturned outer flanges 8 while arranged along the inner sides of the side bars of the frame are beads 9. The outturned flanges 7 are adapted, when the door is in closed position, to press against the face plate 1 and additional face plates 10 secured along the sides 80 of the opening F. The bottom bar of the frame is not formed with an outturned flange 7 but, instead, is adapted to rest flat upon a sill plate 11, as shown in Fig. 2. The inturned flanges 8 are secured to a plate 12 forming the outer surface of the door and secured to the inner side of the plate are angle bars 13. These angle bars are vertical and spaced apart at regular intervals, there being a longitudinally extending head 90 14 formed along the inner end of each bar 13, these heads being disposed in the same plane with the beads 9. Thus it will be seen that fire bricks 15 having longitudinal grooves 16 in their side edges, can be positioned between the sides of the frame 6 and the bars 13, the grooves or channels being occupied by the heads 14 and beads 9 so that the fire bricks will thus be held securely in place. Furthermore air spaces 17 100 will thus be formed between the fire bricks and plate 12. Air inlet openings 18 are formed in the plate 12 close to the lower bar of the frame 6 and air outlet openings 19 are formed in the top bar of the frame 6. 105 Thus it will be seen that air is free to circulate through the spaces 17, the cool air entering the openings 18 and leaving by way of the openings 19. Thus the plate 12 will be kept cool at all times and warping of 110 the door will be prevented.

Brackets 20 are secured to the plate 12 and

the wheels 5 are journaled between the lower ends of these brackets and the plate. An arm 21 extends upwardly from the plate 12 and carries a roller 22 adapted to travel 5 along the face plate 1. Wedging blocks 23 are carried by the upper bar of the frame 6 and are spaced apart distances equal to the distances between the brackets 2. These blocks are of different sizes, the largest block 10 being arranged adjacent one end of the frame 6 and the smallest one being located adjacent the other end of the frame. Thus it will be seen that when the door is moved to closed position, the two smaller blocks 15 will travel between the larger bracket 2 and the face plate 1 and the smaller block will travel between the face plate 1 and the intermediate bracket 2. Finally, as the door comes to closed position, the three blocks 20 will become wedged behind their respective brackets 2, thus causing the door to bind tightly upon the face plates. During this binding operation the wheel 22 will arrive opposite a small recess 24 formed in the face 25 plate 1 so that a slight lateral shifting of the door toward the face plates is thus permitted. The outturned inner flange of the top bar 6 extends at all times back of the lip 3 so that the door is thus prevented from 30 falling laterally away from the face plate 1 while being moved to or from open position. This will be apparent by referring to Fig. 2.

As shown in the drawings a stoking door 24 and an ash door 25 may be provided in 35 the structure of the main door.

What is claimed is:—

1. The combination with a structure having a door opening, of brackets extending out-

wardly from the structure and above the opening, said brackets having depending lips, all 40 of the lips converging in one direction toward the structure, said brackets being of different widths, a door movable into and out of position across the opening and having upstanding wedging blocks movable simultaneously 45 into engagement with the respective lips to bind the door against the structure.

2. The combination with a structure having a door opening and a face plate secured 50 along the top of the opening and formed with a recess, of brackets extending outwardly from the face plate and having depending lips, all of said lips converging in one direction toward the face plate, said 55 brackets being of different widths, a door movable into and out of position across the opening and including a frame having an upstanding flange, said flange being movable between the face plate and the lips, 60 wedging blocks carried by the frame and movable simultaneously into engagement with the respective lips to bind the frame against the face plate, there being a recess in the face plate, and a horizontally revoluble 65 wheel connected to and extending over the door and movable into the recess during such binding action.

In testimony that I claim the foregoing as my own, I have hereto affixed my signature 70 in the presence of two witnesses.

EDWARD M. JONES.
